UNITED STATES PATENT OFFICE.

GEORGE W. AMES, OF STAPLES, MINNESOTA.

GUARD FOR WATER-GLASSES.

1,111,518.

Specification of Letters Patent. Patented Sept. 22, 1914.

Application filed May 10, 1913. Serial No. 766,720.

To all whom it may concern:

Be it known that I, GEORGE W. AMES, a citizen of the United States, resident of Staples, county of Todd, State of Minnesota, have invented certain new and useful Improvements in Guards for Water-Glasses, of which the following is a specification.

My invention relates to a guard or shield for a boiler water glass and the object of the invention is to simplify and improve a similar device for which Letters Patent of the United States issued to me September 6, 1904, No. 769,452.

My invention consists generally in various constructions and combinations, all as hereinafter described and particularly pointed out in the claims.

In the accompanying drawings forming part of this specification, Figure 1 is a side view of a guard or shield embodying my invention, Fig. 2 is a transverse sectional view of the same, on the line $x-x$ of Fig. 1, Fig. 3 is a sectional view on the line $y-y$ of Fig. 1, Fig. 4 illustrates a modified construction, showing the side walls of the guard hinged together, Fig. 5 is a front view of Fig. 4, showing the type of hinge which I prefer to employ.

In the drawing, 2 and 3 represent the valves, tapped into the boiler head in the usual way and 3' the water glass between these valves and communicating therewith, to indicate the level of the water in the boiler. It is customary to provide some sort of a guard or shield around this water glass to prevent the engineer or fireman from being injured by the flying glass in case of breakage or scalded by the discharge of water from the boiler. A device of this kind to be practicable must be of comparatively simple construction and capable of adjustment lengthwise to adapt it for water glasses of various length.

With this end in view I provide two sheet metal plates 4 and 5, bent to a form V-shaped, substantially, in cross section, said plates being placed one above another with their ends telescoping to allow the device to be mounted on a comparatively long water glass or a short one, there being considerable variation in the length of these glasses in different locomotives. The plate 4 forms the lower section of the guard and the plate 5 the upper section. The upper section has wings 6 and 7 which are folded inwardly upon one another to close the top of the

guard, and the lower section has similar wings folded inwardly to close the bottom of the guard, an opening 8 being provided in said wings to allow the guard to be clasped around the necks 9 formed on the valves 2 and 3 and through which the valves communicate with the water glass 3'. The edges 10 of the guard plates are inwardly turned and interlocked with the wings 6 and 7, and between the upper and lower wings of the guard these edges form stops which catch and deflect the glass in case of breakage. The plates 4 and 5 are folded to form panel loops 11 having openings 12 therein opposite similar openings in the plates themselves. Between these openings, on each side of the guard, sections 14 of the glass are inserted, forming transparent panels extending from the top to the bottom of the guard and through which the water glass is plainly visible. The glass panels are supported, as indicated in Fig. 3, by the wings 6 and 7 at the bottom of the guard. These panels are preferably made of a series of small sections of glass. I have found the panel will be stronger made of a series of sections instead of one single piece of glass. There is less expense for repairs in case of breakage and in the adjustment of the device it often happens that the removal or insertion of a section will adapt the panel for the decrease or increase in length of the guard and thereby render it unnecessary to provide an entirely new panel. This one improved feature in the construction of the device has reduced materially the original cost of the articles and its maintenance.

The edges of the guard at the top and bottom are provided with diagonal slots 14' adapted to receive bolts 15 having thumb nuts 16 by means of which the guards can be securely clamped in place on the valves. One of the sections of the guard is also provided with ears 17 having notches 18 therein to receive a bolt corresponding to those at the top and bottom of the guard and having a similar means for tightening the bolt and locking the telescoping ends of the guard sections securely together. The edges of the plates composing the guard extend to a point between the boiler front and the water glass on each side and positively prevent the engineer and fireman from being injured by the flying glass or scalded by the water in case of breakage of the water glass. Whenever desired, the thumb nuts 16 may be

loosened and the guard opened or spread sufficiently to disengage the wings from the water glass and the valve.

In Figs. 4 and 5 I have shown a modified construction, which consists in providing plates 19 and 20 and 19' and 20', arranged in pairs with hinges 21 at their abutting edges, the hinge for the plates 19 and 20 being comparatively short to allow these 10 plates to have a slip-joint connection with the plates 19' and 20', whose hinge, being on the outside, may extend the length of these plates. Panel openings 22 are provided in the plates, in which the glass sections 14 15 are inserted in substantially the same way as described with reference to the previous figures, the panels of one pair of plates sliding by those of the other pair and adapting the guard for water glasses of different 20 length.

I claim as my invention:—

1. The combination, with a water glass and valves therefor, of a sheet metal plate folded vertically along its middle line and 25 inclosing said water glass on three sides and having means for engaging said valves, a clamping device for drawing the edges of said plate together to secure it on said valves, said plate having looped portions 30 formed in the walls thereof on each side of said glass with openings in said looped portions and said plate, and glass panels fitting within said looped portions and through which the water glass is visible.

2. The combination, with a water glass and valves therefor, of a guard interposed between said valves, said guard being V-shaped, substantially, in cross section, having its apex at the front and open at the 40 rear and adapted at the top and bottom to seat on said valves, the rear portions of the walls of said guard having openings therein, rods extending transversely at the rear of said guard and fitting within said openings 45 for drawing the walls of said guard together and clamping them on said valves, said walls having other openings therein, and glass plates fitting within said last named openings and through which plates the water 50 glass is visible.

3. The combination, with a water glass and valves therefor, of a guard interposed between said valves, said guard being V-shaped, substantially, in cross section, having 55 its apex at the front and open at the rear and provided at the top and bottom with inwardly projecting wings arranged to lap by one another and having recesses to receive said valves, the rear portions of the 60 walls of said guard having slotted openings therein, rods extending transversely of the opening at the rear of said guard and fitting within said slots for drawing the walls of

said guard together and clamping said wings on said valves, said walls having other 65 openings therein, and glass plates fitting within said last named openings and through which plates the water glass is visible.

4. The combination, with a water glass and valves therefor, of a guard interposed 70 between said valves and comprising sheet metal sections arranged one above the other in telescoping relation with one another, said section having wings at the top and bottom of said guard provided with recesses 75 to receive said valves, bolts provided at the top and bottom of said guard and connecting the opposite rear walls thereof for clamping said wings on said valves, and one of said sections having a clamping bolt near the 80 middle portion of said guard for locking said sections, one upon another, at the joint between them, said sections having vertical openings therein, and glass plates fitting 85 within said openings, the plates of one section lapping by the plates of the other section to allow freedom of longitudinal adjustment of one section with respect to the other section.

5. The combination, with a water glass 90 and valves whereon said glass is mounted, of a guard composed of upper and lower sections having abutting telescoping ends, said guard having means at the top and bottom for engaging said valves, the rear 95 portion of said guard being open, and means extending transversely thereof for drawing the walls of said guard together to clamp said valves, and means for clamping the adjacent ends of said sections, one upon the 100 other, said sections having openings therein, and a plurality of comparatively small glass plates fitting within said openings, one upon another, the plates at the adjacent ends of 105 said sections lapping by one another, and said plates being readily inserted or removed from said guard for convenience in increasing or decreasing the length of said guard to adapt it for water glasses of different length.

6. The combination, with a water glass 110 and valves therefor, of a guard interposed between said valves, said guard having walls diverging from the front to the rear thereof, an opening being left between the rear portions of said walls, rods bridging said opening and engaging with said walls for clamping them on said valves, said walls having openings through which the water glass is visible, and transparent plates fitting within 115 and closing said openings.

In witness whereof, I have hereunto set my hand this 5th day of May, 1913.

GEORGE W. AMES.
